UNITED STATES PATENT OFFICE.

JOHN S. BARNES, OF DETROIT, MICHIGAN.

FENCE-MACHINE.

No. 847,721.

Specification of Letters Patent.

Patented March 19, 1907.

Application filed February 16, 1906. Serial No. 301,338.

To all whom it may concern:

Be it known that I, JOHN S. BARNES, a citizen of the United States, residing at Detroit, county of Wayne, State of Michigan, have 5 invented a certain new and useful Improvement in Fence-Machines; and I declare the following to be a full, clear, and exact description of the same, such as will enable others skilled in the art to which it pertains 10 to make and use the same, reference being had to the accompanying drawings, which form a part of this specification.

My invention relates to an improvement 15 in fence-machines shown in the accompanying drawings and more particularly set forth in the following specification and claims.

In the drawings, Figure 1 is a plan view of the machine with parts broken away. Fig. 2 is a side elevation of the same. Fig. 3 is a 20 longitudinal section on line x x of Fig. 1. Fig. 4 is a detail view in perspective of the cam-locking roll. Fig. 5 is a detail perspective view of the frame in which the locking-springs are mounted. Fig. 6 is a perspective 25 view of one of the locking-springs. Fig. 7 is a cross-sectional view on line y y of Fig. 1 looking in the direction of the arrow. Fig. 8 is a cross-sectional view on line W W of Fig. 1 looking in the direction of the arrow. Fig. 30 9 is a detail view of a section of one type of fence formed by the machine. Fig. 10 is a detail view of a variation of a device designed to produce a dragging grip on the line-wires.

35 The object of my invention is to construct a fence-machine which may be operated either by manual or mechanical power, but offering particularly little resistance to the operator when operated manually.

40 One of the purposes of my invention is to construct a fence in which the line-wires are composed of two or more strands, then placing several rods of the same under tension, means being provided for twisting the 45 strands of the line-wires between the pickets to engage the same, the direction of the twist alternating between each picket, also providing means whereby the carriage on which the twisting-gears are mounted will travel

50 the entire length of the strained line-wires, the construction being such that any desired space may be provided between pickets, while the distance between the line-wires may be adjusted near or far apart as required.

55 Another object of my invention is to pro-

vide means by which line-wires of different gage may be employed, adjustable means being provided by which the twist given to different gages of wire may be in accordance 6c with the size of the wire employed.

Another feature of my invention is the novel locking and gripping means employed for holding the wire under tension, by which the forward end of the wire is secured, while 65 the other end grips the wire under tension, the construction being such that both ends may be released simultaneously by one operation.

Another important feature of my invention 70 is to insure a uniform length to each of the lateral wires of the fence. This object is accomplished by straining the laterals section by section equally through the entire length of the fence, thereby insuring the laterals of 75 the fence being of a uniform length in order that when the fence is stretched and stapled upon the posts that the pickets of the fence will maintain a perpendicular position throughout when the laterals are under equal 80 tension.

Another feature of the invention is the means whereby the forward end of the lateral wire is held secured, while the opposite end of a two or more rod section is tightly 85 gripped to hold the wire under tension, the construction being such that the wires are permitted to pass through to provide for the undue strain that would otherwise result if both ends of the wire were tightly gripped 90 and then twisted throughout their entire length. By this means a few inches of wire is allowed to pass through the gripping-bar to provide for the increasing strain produced in twisting the laterals.

95 Another feature of the invention is the adjustable means employed for regulating the distance between pickets.

Another feature of the invention is the means employed to deliver the wire to the 100 twisting-gears from the coils in which it is commercially sold.

Other features of the invention will appear by reference to the following specification and claims.

105 In the drawings, A A are the longitudinal members of the frame.

B is a standard secured to the frame A, in which is mounted the locking-cam roll C.

110 B' are cross members secured in the standards B, one of which is provided with a slot B² to receive the downwardly-turned ends

of the locking-springs D. The free ends of these springs are supported by the adjacent bar B'. It will be seen that the springs D may be adjusted laterally along the slotted bar B' in order to provide the required tension on the lateral wires when a change is made in the spacing of the same in constructing the fence. The cam-roll C is provided with a crank-arm C', by which the roll is rotated. A suitable stop c, engaging the crank-arm, is provided to limit the movement of the cam-roll C.

E are standards rising from the distant end of the frame A, in which is mounted the roll E'. This roll may be provided with encircling grooves or not, as desired.

E² is a rocking wire-gripping shaft operated by a crank-arm E³, connected by a cable E⁴, passing about a suitable pulley E⁵ and thence connected with a stud e' at right angles to the crank-arm C', the construction being such that when the locking-cam roll is rotated a rotating movement is also given to the rocking wire-gripping shaft E². The cable E⁴ is provided with a turn-buckle E⁶, Fig. 1, to take up the slack of the wire and to provide for suitable tension on wires of different gage. The rocking wire-gripping shaft is provided with apertures e at fixed intervals throughout its entire length to permit the passage of the strands constituting the line-wires.

F are standards preferably secured to the floor and provided with an adjustable collar f, on which is designed to rest a frame f', provided with openings for the passage of wire. This frame is loosely mounted on the standard F to admit of its free rotation.

G are coils of wire encircling the standards F and resting upon the floor.

H is a collapsible roll mounted on a shaft h, supported in suitable bearings on the end of the machine. This shaft is provided with an operating-crank arm H' and a ratchet h', the ratchet being locked by the dog h², mounted on the frame A. The roll H, which is designed to roll or bundle the fence fabric as it is formed, is provided with a gripping-bar h³ to secure the ends of the longitudinal wires forming the fence.

I is a carriage traveling in suitable ways on the frame A, in which are mounted the twisting-gears J. These twisting-gears are provided with openings through which the strands of the line-wires pass, the construction of the twisting-gears, however, forming no part of the present invention.

J' is a shaft mounted in bearings on the traveling carriage supporting the gears J², which mesh with and drive the twisting-gears J.

J³ is a short shaft sleeved on the end of the shaft J'. Mounted on this shaft J³ is a pinion J⁴, meshing with an idler J⁵, which in turn drives the gear J⁶, loosely journaled on a

shaft mounted in the traveling carriage, its hub having a ratchet engagement J⁷ with the hub of the pinion J⁸. On the opposite end of the shaft J⁹ extending across the machine, is a pinion J¹⁰.

J¹¹ and J¹² are rack-bars mounted on the longitudinal members A of the frame of the machine, the pinions J⁸ and J¹⁰ meshing with the rack-bars J¹¹ and J¹², respectively.

J¹³ is a milled nut having a screw-threaded engagement with the end of the shaft J⁹, by loosening which the gear J⁶ may be thrown out of locking engagement with the ratchet-teeth J⁷ of the pinion J⁸, thereby throwing the carriage I out of operation, as it will be noted that the driving-pinion J⁹ meshes with the idler J⁵ and it with the gear J⁶.

The shaft of the idler J⁵ is secured in a slotted way j, (indicated by the dotted lines in Fig. 1, also shown in Fig. 3,) being secured in said way by a bolt j'. The object of the slotted bearing for the shaft of the idler J⁵ is to provide means whereby intermediate gears of different diameter may be inserted between the pinion J⁴ and the gear J⁶, the change in the diameter of the pinion J⁴ necessitating a like change in the size of the gear J⁶, the object being to provide for twisting strands of different gage. It will be understood that the smaller the gage of wire employed the greater the number of twists required to make a serviceable fence.

I' is a bevel-gear mounted on the shaft J', meshing with an idle bevel-gear I², mounted on the short shaft J¹⁴, supported in the yoke i. The bevel-gear I' is provided with a ratchet-face i', which meshes with a like ratchet formed on the opposing face of the gear J⁴. The bevel-gear I² is also provided with a ratchet-face, as indicated at i², the teeth, however, being cut in the opposite direction to those on I'. The opposing face of the gear J⁴ is also provided with complementary ratchet-teeth.

I⁵ is a crank-arm mounted on the end of the short shaft J³.

It will be seen that by thrusting the gear J⁴ into engagement with the ratchet-teeth on the bevel-gear I' that the twisting-gears will be operated in one direction between one set of pickets. To reverse the twisting of the wire between the next set of pickets, the gear J⁴ is thrown out of engagement with the bevel-gear I' and engaged with the gear I².

M is a pinion mounted on the shaft J'. Meshing with this pinion is a gear M', journaled in suitable bearings in the traveling carriage I. The gear M' is provided with a stop M² to limit the rotation of the gear in one direction.

M³ is an adjustable stop secured to the gear M', by means of which the distance between pickets is controlled, for it will be seen that by the adjustment of this stop the travel of the carriage will be limited in one

direction when said stop comes in contact with the pinion M by the rotation of the gear M' .

To provide means whereby the line-wires 5 may be spaced any suitable distance apart, the twisting-gears J are made adjustable laterally on the frame, which is slotted for this purpose, and are held in position by suitable locking-nuts j^2 . In order to construct a 10 fence having a round-arch picket, as indicated in Fig. 8, I have provided a hood j^3 , which houses the teeth of the first twisting-gear in order to protect the arched portion of the picket from becoming entangled in the 15 teeth of the gear during the rotation of the same. It will be understood that when this type of picket is inserted in the crotch formed by the strands of the line-wire that the arched portion will project to a point 20 equal to the distance between pickets. It is therefore necessary to protect this form of picket from the teeth of the first twisting-gear by hooding the gear.

K is an auxiliary carriage supported in suitable ways on the traveling carriage I , having a shelf K' on which to rest the picket to be inserted, the back of the shelf being provided with an upstanding comb K^2 , between the teeth of which the lateral wires pass.

K^3 are rack-bars supported by the carriage I , and K^4 are gears meshing with the rack-bars and operated by the lever K^5 .

By providing the auxiliary carriage K with a rack-and-pinion movement on both sides 35 of the machine under control of the operating-lever K^5 , I am enabled to drive the pickets into the several crotches with equal force. When the laterals are placed closer together near the ground, as in some forms of field-40 fence, this feature is of particular importance.

L is a hopper to receive the pickets supported in the standards rising from the traveling carriage I .

L' is a hooked arm pivoted in the frame of 45 the hopper, the hook being designed to engage the picket last inserted, so that after the fence fabric is released from the locking devices and is wound upon the winding-drum the carriage I will be drawn to the forward 50 end of the machine in position for operation on a new section of the fence.

I will now describe the operation of my invention.

The coils of wire designed to form the lateral wires of the fence are placed over the standards F , and the inside end of the coil is threaded through the slotted frame f'' and over the roll a , thence through the apertures in the rocking wire-gripping shaft E^2 , thence 60 around the roll E' , through the openings in the twisting-gears, between the wire-locking cam-roll C and the springs D , thence to the collapsible roll H , where it is engaged by the wire-fastening bar h^3 . Tension is then given 65 to the wires by a slight rotation of the drum

H, the operator at the same time engaging both ends of a two or more rod section of lateral wires, as the length of the machine may permit, by operating the wire locking and gripping mechanism. The traveling carriage I is then brought to the forward end of the machine, and the wire is twisted by rotating the twisting-gears. A bundle of loose pickets is placed in the hopper L , and a 70 picket is inserted between the strands of the line-wires and then forced into the crotch of the same by operating the auxiliary carriage K , provided with the comb K^2 , which carries the picket snugly into the crotch. The crank-arm I^5 is then rotated, twisting the 75 line-wires together and around the picket, thus locking the picket in position, the length of the twist between pickets being controlled by the position of the stop M^3 on the gear M' . When the line-wires have been 80 twisted a suitable distance, as controlled by the stop referred to, a new picket is inserted between the strands of the line-wire and forced into the crotch by operating the lever K^5 , controlling the movement of the auxiliary carriage K . The crank-arm I^5 is again 85 operated, the ratchet on the face of the gear J^4 being first thrust into the ratchet of the opposite bevel-gear, thus reversing the movement of the twisting-gears J and causing 90 the twisting of the strands to be formed in the opposite direction to that between the preceding pickets last inserted. This operation is repeated and continued until the 95 entire length of the line-wires under tension 100 is formed into fence fabric. It will be seen that as the section of lateral wires is twisted around the pickets that the tension would naturally increase. To provide for the increasing strain, the construction of the wire-gripping bar E^2 is such that the lateral wires 105 will draw through the apertures e , which are of sufficient size to permit this movement, thereby compensating for the undue increasing strain on the laterals which would otherwise result. The locking mechanism holding the wires under tension is then released by a movement of the crank-arm C' , controlling the cam-roll C and the rocking wire-gripping 110 shaft E^2 , thus permitting the wire to pass 115 freely through the same. The fence fabric is now wound upon the collapsible drum until the last picket reaches a position adjacent to the cam-locking roll, when the lateral wires are again put under tension and 120 locked. It will be seen that as the fabric is wound upon the collapsible drum that the traveling carriage will be drawn forward, due to the engagement of the hooked bar L' with the picket last inserted. The operation 125 just described is now repeated until the required length of fence is formed.

The variation shown in Fig. 10 for producing the dragging grip on the strands of the line-wires shows a construction wherein 130

should it become necessary to change the distance between the lateral wires in making up the different styles of fence the wires may be set any predetermined distance apart 5 without rethreading the machine, as would be required in the form shown in the other figures. It will be readily understood that in order to do this all that will be required is to rotate the gripping-bar sufficiently to release the tension, when the wires may be adjusted laterally to meet the purposes of the fence. This is accomplished by forming the gripping-bar E² with an elongated slot extending the width of the machine, or the bar 10 may consist of two strips placed side by side, leaving a space between for the passage of the wires, the ends of the bar being set in hubs supported in the frame of the machine and free to rotate therein, as shown in the figure 15 referred to. Engaging one end of the gripping-bar is the crank-arm E³, to which is engaged the cable E⁴ for operating the same, as shown in Figs. 2 and 3 of the drawings.

An important feature of my invention 20 heretofore referred to consists in the fact that the length of the machine may be added to or reduced as required by inserting or removing sections of the longitudinal members of the frame E, which are connected together at the points A', (shown in Fig. 1,) where they are secured together by suitable locking devices. By this means I am enabled to put any desired length of the line-wires of the fence under tension.

Having thus described my invention, what 25 I claim is—

1. In a wire-fence machine, means for placing and holding the strands of wire constituting an extended section of the line-wires of the fence under tension, means for 30 twisting said strands together from picket to picket inserted between the said strands while under tension, and means for bundling the finished product after the tension on the line-wires is released, substantially as described.

2. In a wire-fence machine, means for gripping and putting under tension an extended length of the strands constituting the line-wires of the fence, means for twisting said strands together from picket to picket, means for reversing the direction of the twist given to said strands between each alternate picket, and means for bundling the finished product 35 when released by the tension mechanism, substantially as described.

3. In a wire-fence machine, means located between the wind-up or bundling drum and the feed-wire reels of the machine for putting an extended section of the line-wires of a fence under tension, said means consisting of devices for gripping the line-wires at one end and provided with means for producing a dragging grip on the opposite end of the extended section, the construction being such

as to permit the passage of wire to relieve the increasing strain caused by twisting the strands together, and means for twisting said strands together throughout the length of said extended section between and around the pickets, substantially as described. 70

4. In a wire-fence machine, means for gripping one end of the line-wires of an extended section of fence consisting of a rocking cam-roll journaled in the frame of the 75 machine, means for rocking said cam-roll, springs housed below said rocking cam-roll in the frame of the machine, the construction being such that the line-wires pass between said springs and the rocking cam whereby 80 said cam when partially rotated will grip said wires between the cam and the springs, substantially as described.

5. In a wire-fence machine, means for gripping one end of the line-wires consisting 85 of a rocking cam-roll journaled in the frame of the machine, means for rocking said cam-roll, springs housed within the frame of the machine below said cam-roll adapted for lateral adjustment, the construction being such that 90 said springs may be set so that the line-wires may pass between the springs and the rocking cam however spaced, whereby said cam when partially rotated will grip said wires between the cam and the springs, substantially as described. 95

6. In a wire-fence machine, means located between the wind-up or bundling drum and the feed-wire reels of the machine for putting an extended section of the line-wires of the 100 fence under tension, said means consisting of devices for gripping the line-wires at one end and providing a dragging grip on the opposite end of an extended section, substantially as described.

7. In a wire-fence machine, means located between the wind-up or bundling drum and the feed-wire reels of the machine for putting an extended section of the line-wires of the fence under tension, said means consisting of devices for gripping the line-wires at one 105 end and providing a dragging grip on the opposite end of an extended section, a reciprocating carriage adapted to travel the length of said extended section provided with twisting-gears for twisting the strands of the line-wires together between and around the pickets, driving-gears for operating said twisting-gears and also the reciprocating carriage, substantially as described. 110

8. In a wire-fence machine, means located between the wind-up or bundling drum and the feed-wire reels of the machine for putting an extended section of the line-wires of the fence under tension, consisting of devices 115 for securely gripping the line-wires at one end and provided with means for producing a dragging grip on the opposite end of an extended section, a reciprocating carriage on which are mounted twisting-gears designed 120

125 130

to twist the strands forming the lateral wires together, suitable driving-gears to operate the twisting-gears and to control the movement of said carriage, substantially as described.

9. In a wire-fence machine, means located between the wind-up or bundling drum and the feed-wire reels of the machine for putting an extended section of the line-wires under tension, said means consisting of devices for securing the line-wires at one end and providing a dragging grip on the same at the opposite end of the extended section of line-wires, a reciprocating carriage on which are mounted twisting-gears for twisting together the strands between and around the pickets of the fence, and means for determining the distance between pickets in said twisted section, said means being adjustable to adapt it for varying conditions, substantially as described.

10. In a wire-fence machine, a reciprocating carriage on which are mounted twisting-gears for twisting the strands of the line-wires together between and around the pickets of the fence, means for reversing the direction of the twist between alternate pickets, and adjustable means for regulating the distance twisted between pickets, said means consisting of a movable stop secured to a gear driven by the driving-gear, the construction being such that the movement of the gear will cause the stop to come in contact with the driving-gear, thus stopping the rotation of the twisting-gears and indicating the predetermined distance between pickets, substantially as described.

11. In a wire-fence machine, a reciprocating carriage on which are mounted twisting-gears for twisting together the strands forming the line-wires of the fence, the construction being such that the gearing operating the twisting-gears will control the travel of the carriage, means for stopping the movement of the twisting-gears when the strands are twisted a predetermined distance between pickets consisting of an adjustable stop secured to one of the operating-gears arranged to limit the movement of said gear in any one direction, substantially as described.

12. In a wire-fence machine, a reciprocating carriage on which are mounted twisting-gears to twist together the strands forming the line-wires of the fence, the construction being such that the movement of the said carriage will be regulated by the predetermined travel of the twisting-gears, means for reversing the direction of the twist between alternate pickets, and means for regulating the number of times said strands are twisted together between pickets and the distance from one picket to the next, substantially as described.

13. In a wire-fence machine, means located between the wind-up or bundling drum

and the feed-wire reels of the machine for putting an extended section of the line-wires of the fence under tension consisting of gripping devices at one end and tension devices at the other end of the machine to engage the extended section of the line-wires, a traveling carriage designed to reciprocate between the ends of said line-wires, said carriage provided with twisting-gears through which the strands of the line-wires pass, suitable gearing meshing with said twisting-gears and operated through a driving-gear meshing with the rack-bars over which the carriage travels, and means consisting of a suitable clutch mechanism for throwing the driving-gear in or out of engagement, substantially as described.

14. In a wire-fence machine, means for putting an extended section of the line-wires of the fence under tension, consisting of devices for gripping the line-wires at each end of the extended section, a reciprocating carriage adapted to travel the length of said extended section on which are mounted twisting-gears for twisting the strands forming the line-wires of the fence together between and around the pickets, said twisting-gears operated by means of gearing engaging a rack mounted on the frame of the machine, the construction being such that the movement of the carriage along the rack is controlled by the predetermined travel of the twisting-gears, substantially as described.

15. In a wire-fence machine, means located between the wind-up or bundling drum and the feed-wire reels of the machine for putting an extended section of the line-wires under tension, said means consisting of devices for securing the line-wires at one end and providing a dragging grip on the opposite end of the extended section, a reciprocating carriage on which are twisting-gears to twist together the strands forming the line-wires of the fence, and means for reversing the twist between alternate pickets, substantially as described.

16. In a wire-fence machine, a reciprocating carriage on which are mounted the twisting-gears for twisting together the strands forming the line-wires of the fence, means for holding the line-wires under tension by suitable gripping devices forming part of the machine, an auxiliary carriage mounted on said traveling carriage having a comb between the teeth of which the strands of the line-wires pass, said auxiliary carriage mounted on a rack and operated by a pinion meshing with the rack on the frame of the machine and controlled by a suitable operating-lever, substantially as described.

17. In a wire-fence machine, means for gripping an extended length of the strands constituting the line-wires of the fence, adjustable means for twisting said strands together from picket to picket, the construc-

tion being such that the twist may be regulated to the distance between pickets and the gages of wire employed, substantially as described.

- 5 18. In a wire-fence machine designed to hold extended lengths of wire strands under tension while twisting them together to form the line-wires of the fence, means for producing a dragging grip on the strands of wires, 10 the construction being such that when it becomes necessary to change the distance between the line-wires they may be adjusted laterally without rethreading the machine, substantially as described.
- 15 19. In a wire-fence machine designed to hold an extended section of the strands forming the line-wires of the fence under tension,

means for producing a dragging grip consisting of two bars mounted in adjacent relation between which the strands of the line-wires 15 pass, said bars suitably mounted whereby they may be given a rocking movement producing a dragging grip on the wires, the construction being such that the strands forming the line-wires may be given a lateral adjustment without rethreading the machine, substantially as described.

In testimony whereof I sign this specification in the presence of two witnesses,

JOHN S. BARNES.
